F. J. MILLER

LOCKING RECEPTACLE

Filed June 9, 1922

Fig. 1

INVENTOR.
Fred J. Miller
ATTORNEY
Jas. R. Daingerfield

UNITED STATES PATENT OFFICE.

FRED J. MILLER, OF BELLEVUE, PENNSYLVANIA.

LOCKING RECEPTACLE.

Application filed June 9, 1922. Serial No. 566,980.

To all whom it may concern:

Be it known that I, FRED J. MILLER, a citizen of the United States, residing at Bellevue, in the county of Allegheny and State of Pennsylvania, have invented certain new and useful Improvements in Locking Receptacles, of which the following is a specification.

This invention relates to certain new and useful improvements in locking receptacles, more particularly to a locking mechanism therefor somewhat similar to that disclosed in my patent numbered 1,356,301, and bearing date the 19th day of October, 1920, and besides embodying the objects and advantages as set forth in connection with the construction, embodied in said patent, has for its further object to improve and simplify the locking mechanism, thereby augmenting the efficiency of the device and providing for its economical construction.

Further objects of the invention are to provide a locking receptacle primarily designed for the reception of milk bottles, although it is to be understood that it can be employed for any purposes wherein it is found applicable, with means operable by the bottle closure or cap thereof, when the bottle is placed within the receptacle, for locking the lid of the latter to prevent surreptitious removal of the bottle from the receptacle which is simple in its construction and arrangement, durable and efficient in its use, and attractive in appearance.

To the accomplishment of these and such other objects as may hereinafter appear the invention consists of the novel construction, combination and arrangement of parts herein specifically described and illustrated in the accompanying drawing wherein is shown an embodiment of the invention, but it is to be understood that changes, variations and modifications may be resorted to which come within the scope of the claims hereunto appended.

In the drawing forming a portion of this specification, and wherein like numerals of reference designate corresponding parts throughout the several views:—

50 Figure 1 is a front elevation of a locking

receptacle in accordance with this invention.

Figure 2 is a vertical sectional view on line II—II, Figure 1.

Figure 3 is an enlarged detail inner view of the locking mechanism. 55

Figure 4 is a sectional view on line IV—IV, Figure 3.

Referring in detail to the drawing 1 denotes the body portion of the receptacle, preferably constructed from sheet metal and rectangular in contour. The body portion 1, as illustrated is divided into three vertical circular compartments 1, 2, 3, respectively, each adapted for the reception of a milk bottle 4, but it is obvious that the receptacle may have any number of compartments to best meet conditions found in practice. 65

The compartments 1, 2, 3 are formed of tubes made from any suitable material, and the entire top of the body portion 1 is covered with a closure plate 5, leaving only the upper ends of the compartments 1, 2, 3, open. 70

The space intervening between the tubes, forming the compartments 1, 2, 3, and the side and end walls of the body portion 1, forms an air chamber 6 surrounding the tubes, providing a comparatively even temperature within the compartments, and thereby preventing deterioration from heat or cold of the milk or other products stored in the compartments for an unusual length of time. 75

The body portion 1 is provided with a lid 7, hinged, as at 8, to the top edge of the rear wall of the body portion. 85

A lock casing 9, is fixed to the under face of the lid 7, centrally of its forward portion, by means of rivets 10, which extend through the lateral flanges 11 formed integral with casing 9. 90

A longitudinally extending latching bar 12 is pivotally mounted, as at 13, in the casing 9, and has its rear end 14 projecting through a slot 15 formed in the rear end wall of the casing 9, and its forward end 16 projecting through a slot 17, formed in the front wall of the casing 9. The slots 15 and 17 are of greater length than the width of the 95 100

latching bar 12, extending therethrough, to permit of the lateral movement of the latter in said slots for purposes hereinafter described.

5 The casing 9 is so positioned on the lid 7 as to allow the forward end 16 of the latching bar 12 to extend to the inner face of the front wall 18 of the body portion 1.

10 Pivotedly mounted, as at 19, on the inner face of the front wall 18 of the body portion 1, and extending upwardly through a slot 20 formed in the closure plate 5, is a locking member 21, having its upper end formed to provide a catch 22 adapted to engage the forward end 16 of the latching bar 12.

15 The lower portion 23 of the locking member 21, extending below its pivotal connection 19, is engaged by a flat spring 24, which latter is mounted on the inner face of the front wall 18 of the body portion 1, as is indicated at 25. The action of the spring 24 normally tends to force the catch 22 in a direction toward the latching bar 12, but 20 such movement is limited by the length of the slot 20 through which it extends. The locking member 21 is actuated to release the latching bar 12 by a key ward, which latter is adapted to engage the lower portion 23 of 25 the locking member 21 when the key is operated through the key hole 26, provided therefor, in the front wall 18 of the body portion 1.

30 A spring 27, attached to the latching bar 12, as at 28, forward of its pivot 13, and abutting against a side wall of the casing 9, normally forces the forward end 16 of the bar 12 away from the catch 22 of the locking member 21. Such lateral movement 35 of the bar 12, however, is limited by the length of the slot 17 through which the forward end 16 of the bar extends.

35 Carried on the free end of a flat spring 29 is a plunger 30, which depends laterally 40 through an aperture 31, provided therefor, in the casing 9. The forward end of the spring 29 is fixed to the forward end of the casing 9, as indicated at 32.

45 The upper end of the plunger 30 is 50 tapered, as at 33, and is so positioned in the aperture 31, that when the plunger is forced upwardly the upper tapered end thereof will engage the side of the latching bar 12, in rear of its pivot 13, and shift the rear 55 end 14 of the bar 12, laterally in one direction in its slot 15. The other end 16 of the bar 12 will be shifted laterally in its slot 17 in the opposite direction and will engage the catch 22 of the locking member 21, and 60 secure the lid 7 in locked position so long as the plunger 30 is held upwardly to engage the latching bar 12 or until the locking member 21 is actuated by a key to release the catch 22.

65 The plunger 30 is positioned in the casing

9 to extend centrally over the top of the milk bottle 4 in the center compartment of the body portion 1. When no bottle is in the compartment 2 the lid 7 cannot be locked as the latching bar 12 and locking member 21 remain disengaged by the action of respective springs 27 and 24. But when a bottle is positioned in the compartment 2, and the lid 7 is closed, the lower end of the plunger 30 will strike the closure cap 34 on the bottle and will be forced upwardly, actuating the latching bar 12 to engage the catch 22 of the locking member 21. After being locked in this manner, the lid can only be opened by the key.

70 The lower end of the plunger 30 is formed with a flange 35 to provide a better working face therefor and prevent liability of its cutting the closure cap 34. Only the bottle positioned in the compartment directly beneath the plunger 30 will serve to act as 75 a locking medium for the receptacle.

80 What I claim is:—

1. A receptacle comprising a body portion 90 provided with a hinged lid, a key operated locking member carried by the body portion, a spring controlled and pivoted latching member carried by the lid and engaging with the locking member for maintaining the lid closed, a resilient member supported from the lid and opposing the latching member, and a shiftable plunger carried by the resilient member and actuated by an object within the body portion for swinging the latching member to engage the locking member. 95

100 2. A receptacle comprising a body portion provided with a hinged lid, a key operated locking member carried by the body portion, a spring controlled and pivoted latching member carried by the lid and engaging with the locking member for maintaining the lid closed, a resilient member supported from the lid and opposing the latching member, and a shiftable plunger carried by the resilient member and actuated by an object within the body portion for swinging the latching member to engage the locking member, said plunger having its upper end 105 tapered. 110

115 3. A receptacle comprising a body portion provided with a hinged lid, a vertically disposed and pivoted key operated locking member carried by the body portion, a spring controlled and pivoted latching member carried by the lid and engaging with the locking member for maintaining the lid closed, a resilient member supported from the lid and opposing the latching member, and a shiftable plunger carried by the resilient member and actuated by an 120 object within the body portion for swinging the latching member to engage the locking member. 125

130 4. A receptacle comprising a body portion provided with a hinged lid, a vertically

disposed and pivoted key operated locking member carried by the body portion, a spring controlled and pivoted latching member carried by the lid and engaging with the locking member for maintaining the lid closed, a resilient member supported from the lid and opposing the latching member,

and a shiftable plunger carried by the resilient member and actuated by an object within the body portion for swinging the latching member to engage the locking member, said plunger having its upper end tapered. ¹⁰

In testimony whereof I affix my signature.

FRED J. MILLER.
